UNITED STATES PATENT OFFICE.

NATHANIEL HARRIS, OF ST. LOUIS, MISSOURI.

SASH-HOLDER.

SPECIFICATION forming part of Letters Patent No. 600,283, dated March 8, 1898.

Application filed November 4, 1897. Serial No. 657,384. (No model.)

To all whom it may concern:

Be it known that I, NATHANIEL HARRIS, a citizen of the United States, residing at St. Louis, in the State of Missouri, have invented 5 certain new and useful Improvements in a Combined Sash-Balance and Antirattler, of which the following is a full, clear, and exact description, reference being had to the accompanying drawings, forming a part hereof.

10 My invention has relation to improvements in a combined sash-balance and antirattler; and it consists in the novel arrangement and combination of parts more fully set forth in the specification and pointed out in the claim.

15 In the drawings, Figure 1 is a perspective view of my complete invention, showing in dotted lines the sash and window-frame. Fig. 2 is a horizontal cross-section of a window-frame and sash, showing my invention applied thereto. Fig. 3 is a horizontal cross-section of the plate properly formed with the spring removed. Fig. 4 is a plan-view of the blank from which my invention is formed 20 with spring removed; and Fig. 5 is a horizontal cross-section of a window-frame and sash, showing my invention as attached to the sash and pressing against the frame.

25 The object of my invention is to construct a simple, cheap, and effective combined sash-balance and antirattler whereby the window may be held by friction at any desired position and at the same time prevented from rattling; and it consists of a plate adapted to be secured to the window-frame and having 30 a wing formed at right angles thereto, to which wing one end of a flat spring is secured, the opposite free end of said spring being in frictional contact with the wing, the medial portion of the spring normally extending beyond 35 the longitudinal edge of the plate, whereby when the whole is properly applied the spring will frictionally bear or press against the sash; and it further consists in other details hereinafter more fully set forth.

40 In detail the invention may be described as follows:

45 Referring to the drawings, 1 represents a flat plate of sufficient length, having a longitudinal straight edge 2.

50 3 3 represent ears, each of which is provided with an opening 4, through which suitable

fastening devices, such as nails or screws 5, are passed for securing the plate to the guide-strip 6 of the window-frame 7, with the longitudinal edge 2 parallel and adjacent to the 55 sash 8, as best shown in Fig. 2. Formed integral with the plate 1 and located between the ears 3 3 is a wing 9, bent approximately at right angle to the plate 1, and attached to the plane flat surface of said wing, adjacent to 60 the upper edge thereof, is one end of a bowed spring 10, the parts being preferably united by a rivet 11. The opposite or free end of said spring 10 bears against or presses on the flat surface of the wing adjacent to the opposite lower edge of the same. The medial portion 12 of the spring normally extends beyond the longitudinal straight edge 2 of the plate, whereby when the plate is secured to the 65 guide-strip of the frame, with its longitudinal 70 edge 2 adjacent to the sash, the spring 10 will frictionally bear against the sash and be depressed as far as the edge 2.

In Fig. 4 I have shown the blank from which the plate, ears, and wing are formed, the same 75 being oblong in shape and cut or sheared at 13 to a suitable distance and the portion 14 bent on the dotted lines 15 to form the wing, this being the preferred method of forming 80 the plate; but the same may be cast or otherwise formed without departing from the nature of my invention.

In some instances, and especially where new frames and sashes are set up, the device is preferably applied as shown in Fig. 5, the 85 plate being secured to the sash and the spring bearing against the inner adjacent surface of the guide-strip of the window-frame, whereby the plate, together with its spring, is entirely hidden from view. In applying my invention in either instance a sufficient amount of material is cut either from the guide-strip or sash to accommodate the wing and spring carried by the same.

When my invention is applied as shown 95 in Fig. 5, the ears are set in flush with the sash, and when applied as shown in Fig. 2 they may or may not be set into the guide-strip, as may be found most desirable.

By the employment of the longitudinal 100 edge 2 of the plate the device can be easily and quickly adjusted and fastened to any

window-frame and sash and the spring prevented from being depressed beyond a point that would totally destroy or injure the same.

Having fully described my invention, what 5 I claim is—

A combined sash-balance and antirattler, consisting of a plate, securing-ears formed with said plate and on a plane with the same, a wing also formed with said plate, and bent 10 at right angles thereto, the length of which is equal to the distance between the ears, a bowed spring one end of which is secured to the wing and having its opposite free end in frictional contact with the same, the width

of said spring being substantially the same 15 width as the said wing, the said plate and ears having a continuous longitudinal straight edge, and the medial portion of said spring normally extending beyond the longitudinal straight edge of the plate, substantially as 20 described.

In testimony whereof I affix my signature in presence of two witnesses.

NATHANIEL HARRIS.
